UNITED STATES PATENT OFFICE.

HOWARD E. K'BURG, OF CLEVELAND HEIGHTS VILLAGE, OHIO, ASSIGNOR TO UNDER-
WOOD TYPEWRITER COMPANY, OF NEW YORK, N. Y., A CORPORATION OF DELAWARE.

TYPE-WRITING MACHINE.

1,259,630.

Specification of Letters Patent. Patented Mar. 19, 1918.

Application filed January 14, 1916. Serial No. 72,013.

To all whom it may concern:

Be it known that I, HOWARD E. K'BURG, a citizen of the United States, residing in Cleveland Heights Village, in the county of Cuyahoga and State of Ohio, have invented certain new and useful Improvements in Type-Writing Machines, of which the following is a specification.

This invention relates to mechanism for use on type-writing machines to enable work-pieces inserted one after another to be quickly and accurately superposed on the platen. The invention is particularly adapted for the arrangement of work, wherein work-sheets or units are placed on the platen in a predetermined relative position with their leading edges one in advance of another. For instance, it is customary, in some systems of bookkeeping, to collate an invoice sheet, statement, or the like on the platen, together with a ledger leaf to receive the typewritten entries. The entries from a number of different bills or statements are ordinarily made on a single ledger sheet, the latter being placed on the platen with its leading edge more or less in advance of the leading edge of the bill or statement. It is also important to attend to the lateral adjustment of the sheets, so that the vertical columns in which the original entries are typewritten, shall be in accurate register with the corresponding columns of the underlying sheet. Some suitable means is accordingly desirable to enable the sheets to be quickly and accurately collated on the platen in such relative position. An object of the present invention is to provide such means.

Preferably a chute or guide is provided at the introductory side of the platen on which the sheets may be placed and advanced around the lower face of the platen, up past the printing line, and onto a sheet-supporting and collating table at the delivery side of the platen, said table extending upwardly and rearwardly beyond the front face of the platen. The chute and table are preferably both provided with gages for the lateral edges of the work-sheets, a gage on the chute for one edge of a sheet (for example, the left-hand edge) being preferably in alignment with the corresponding gage on the table.

In collating the sheets, the sheet or unit

to receive the carbon impression may be dropped into the chute at the introductory side of the platen and pushed forwardly, being guided by said chute around the platen, and moved upwardly into position to receive the first line of writing. The sheet may be accurately adjusted and held in adjusted position by the thumb or finger of the operator bearing against the sheet near the right-hand edge thereof and holding it firmly against the supporting table; the sheet having been preferably adjusted so that its left-hand edge abuts against the corresponding edge on the table, whereby the sheet is squared relatively to the printing line on the platen. While the operator holds the sheet in such position with his right hand, the sheet (as for example, a ledger sheet) to receive the original typewritten entry is dropped down the chute behind the first sheet and pushed forwardly to bring its leading edge up over the supporting table in front of the platen. The operator may then, with his left hand, grasp the upper or leading end of the outer sheet and advance or retract it to position it for the first line of writing, the sheet at the same time being adjusted and squared to the left-hand margin-gage; or, in other words, said outer sheet is brought into register with the underlying invoice or statement. The outer or ledger sheet is ordinarily somewhat narrower than the underlying printed form, and when in proper register with the latter, the left-hand edges of the sheets are together, so that the right-hand margin of the underlying sheet projects laterally beyond the overlying sheet, so that the operator may hold the underlying sheet without interference with the upper sheet.

The front surface of the supporting table may be roughened or provided with roughened portions to underlie the margins of the work-sheets, and thereby aid in firmly holding them in adjusted position. When the sheets have been adjusted, they are held in position by the usual feed rolls at the underside of the platen, said rolls having been temporarily thrown off the platen to permit the collation of the work-sheets.

One of the principal objects of the invention is to provide a simple and inexpensive means, readily adaptable to existing machines, for writing at a single operation the

bill, the ledger entry and the corresponding entry in the day-book or journal or other bookkeeping record; the bill entry usually comprising several lines of typewriting, each line usually including not only amounts, but also explanatory words entered opposite the amounts, and the items for all the customers usually following one another upon the day-book, journal or other record. Successive bills for the same customer usually follow one another down each ledger page, thus necessitating the collation of the bill and the ledger in different relative positions for successive bills. It has heretofore been the practice to collate the ledger sheet, the bill and the general record sheet all upon the platen, and to remove all three after the writing of every bill; but, according to one feature of my improvements, the general record sheet is made in the form of a web which does not need to be removed from the machine, but may remain there and be wound or fed along until filled up, containing the entries for all the customers in the order in which they are written upon the various ledger sheets and bills. I arrange this record sheet nearest to the platen, and collate thereon the ledger sheet and bill, so that the items for all the customers follow one another properly upon the record sheet, while all the items for a single customer follow one another upon the ledger sheet. For the ledger and bill collating, I place the collating table directly over the general record web, so that all three sheets are held properly at the printing line to receive the type impressions, while the table may serve for the collating of the bill and ledger sheet without disturbing the web, which advances under the table. The width of the web may be nearly equal to the width of the collating table, so as to receive all or at least the main portions of the typewriting; and the web may be connected to the same line-spacing handle that advances the platen, so that the web shall be fed line by line with the bill and ledger sheet, thus distinguishing from the ordinary tally-strip mechanism where the tally-strip merely contains the amount and is line-spaced by the feed-roll-release mechanism. For economy of space and paper, the machine is preferably arranged so that the general web will not be advanced so far as the bill and ledger sheet; and to this end a suitable provision may be made in the line-spacing devices of the web. The feed rolls which hold the bill and record sheet upon the platen, need not press upon those parts of the platen which are occupied by the record web, so that the bill and record sheets may advance faster than the web, as desired.

The web may be in the form of a roll supported upon the usual platen frame, pref-

erably forward of the above-described chute. From the roll the web may run to and around the platen, between the latter, and the ledger sheet and bill, and preferably between the platen and the collating table, to a winding spindle behind said table; and the web may be wound upon said spindle by means of a train of gearing connecting the spindle with the platen line-spacing mechanism. The web will thus contain duplicates of the invoices that are written upon the separate work-sheets. The collating table may have sheet-supporting upward extensions at its ends, or, in other words, it may have its upper middle portion cut away sufficiently to permit access by the operator to the web mechanism and other parts behind the table, for example, the chute. The sides of the chute are so placed as to deliver the sheet from said chute approximately to the squaring gage on the collating board, the head whereof may be clear, or unprovided with any obstructive appliance, to permit the collation on the table of a long sheet which projects upwardly beyond the table, when required.

Other features and advantages will hereinafter appear.

In the accompanying drawings, Figure 1 is a front perspective view of an Underwood typewriter carriage, with the present invention applied thereto.

Fig. 2 is a sectional elevation of the same.

Fig. 3 is a front elevation illustrating the manner in which the work-sheets are adjusted by the operator.

Fig. 4 is a sectional view, partly diagrammatic, showing the arrangement of the work-sheets and tally-strip mechanism.

A roller platen 5 is mounted upon an axle 6, having bearings in the right and left-hand ends 7 and 8 of the platen frame. Said frame also comprises a paper-shelf 9 connecting said ends, the shelf extending upwardly and rearwardly from the introductory side of the platen.

The platen frame may be mounted as usual to shift up and down to the different case positions on the carriage frame 10. Types 11, operated by the usual mechanism, strike against the front face of the platen. The platen may be rotated by hand-wheels 12 on the platen axle, or by the usual line-spacing mechanism comprising a line-spacing lever 13 operable to move rearwardly a slide bar 14 which carries a dog arranged to drive a line-space ratchet wheel 15 fixed to the platen axle, and thereby rotate the platen.

Feed rolls 16 bear against the under surface of the platen and coöperate therewith to advance the work-pieces. The feed rolls may be thrown off the platen by a release key 17 connected through a link 18 to an arm 19 on a rock shaft 20. Levers 21 fulcrumed

on a tie-rod 22 of the platen frame have depending arms 23 to engage flats or cams 24 on the shaft 20, so that when the key 17 is depressed and the shaft 20 thereby rocked, 5 the feed rolls are moved downwardly away from the platen.

A chute 25 is provided at the introductory side of the platen by which the work-sheets may be guided to and around the 10 platen. Said chute preferably overlies the paper-shelf 9, which forms a support for said chute; the latter having a forwardly extending portion 26 curved to conform to the curvature of the platen and spaced therefrom to provide a passageway through which the work-sheets are guided. The chute is preferably formed with right and left-hand flanges 27 and 28 perpendicular to the face of the chute and forming gages 15 for the lateral edges of the work-sheets. The gages 27 and 28 preferably extend with the part 26 around the underside of the platen, forming end walls for the passageway beneath the platen. The side flanges of the 20 chute may, if desired, be enlarged to form side plates 29, which completely surround the platen. The construction and arrangement of the chute may be similar to that disclosed in the copending application of J. A. 25 B. Smith, Serial No. 56,857. The chute is supported in part by a tie-rod 30 of the platen frame, which rod extends through openings in the side plates 29. If desirable, the chute may be adjustable along said rod 30 to different positions lengthwise of the platen.

Mechanism for supporting and feeding a web around the platen, is supported on brackets 31 and 32 on the platen frame ends 40 8 and 7, respectively. The supply-roll 33, which may comprise a web 34 and a carbon-strip 35, is mounted on a rod 36 removably supported in the brackets 31 and 32. From said supply roll the web and its carbon extend downwardly to the platen and around the under surface of the platen, thence upwardly over a guide roll 37, and from said roll to a winding spindle 38. The roll 37 is mounted on a shaft 39 journaled at its 45 ends in the brackets 31 and 32. The winding spindle 38 is mounted in a frame 40, the ends of said frame being connected by tie-rods or bars 41 and 42, the latter providing a tearing edge for the web.

50 The winding spindle 38 may be driven by the line-spacing mechanism, to line-space the web each time the line-space lever is operated to line-space the work-sheets. A train of gearing between the line-spacing lever 13 and said spindle, for rotating the latter, comprises gear wheels 43 and 44 connected to said spindle and the shaft 39, respectively, and intermeshing gear pinions 45 and 46 secured, respectively, to the shaft 39 and a 55 stub shaft 47 mounted on the bracket 31.

A ratchet wheel 48 fixed to the shaft 47 is driven by a pawl (not shown) carried by a rock arm 49, which arm swings on the shaft 47 and is connected through a link 50 with the slide bar 14. This web-winding mechanism is disclosed and claimed in patent to Hart, Reissue No. 14,283, of April 10, 1917.

The work-sheets, as they move upwardly over the front face of the platen, are guided onto a work-supporting and collating table 51, which extends upwardly and rearwardly from the front face of the platen. Said table may be mounted on brackets 52, the latter connected to the rod 30 and shaft 39. The connection between the table 51 and the brackets 52 may comprise screws 53 extending through slots 54 and threaded into the brackets, the heads of the screws being seated in depressed or offset portions of the table, so that said heads will not project above the surface of the table, thus preventing interference of said heads with the sheets on the table. The connection just described permits adjustment of the table toward or from the platen. The lower edge 90 of the table is slightly spaced from the platen to permit the passage of the general record web between the table and platen, the web passing upwardly behind the table where it does not interfere in any way with 95 the adjustment of the work on the table. The table with its supporting brackets 52 may be made adjustable to different positions lengthwise of the platen if desired.

The table is provided at one or both of its lateral edges with flanges as 55 and 56, which form gages for the lateral edges of the work-sheets. The left-hand flange 55 may be in register, that is, in the same vertical plane, with the gage 28 on the chute 25, 105 so that a work-sheet adjusted to the gage 28 will also be in contact with the gage 55. The chute 25 and work-table 51 are preferably, but not necessarily, the same length, so that the right-hand gages 27 and 56 may 110 also be in register. The table is formed with extensions having roughened surfaces 57 to prevent slipping of the work thereon, particularly while a sheet is temporarily held on the table by the operator during the 115 adjustment of the overlying sheet.

The body portion of the work-table 51 may be comparatively narrow, the end portions 58 thereof being extended upwardly, so that the surfaces 57 on which the margins 120 of the work-sheets rest are of considerable length, as are also the gages 55, 56, so that the sheets are amply supported and easily and accurately gaged; while the table being cut away between the lateral extensions 58, 125 exposes to view the web mechanism, and does not interfere with the manipulation of the web and its mechanism.

In adjusting the work-pieces on the platen for writing, the key 17 is depressed to throw 130

the feed rolls off the platen, and the inner work-sheet or unit 60 is introduced either backwardly from the front of the platen or forwardly from the rear of the platen, 5 preferably the latter. That is, the sheet is placed on the chute 25 and pushed forwardly, being guided around the platen between the latter and the extension 26 of the chute, so that the leading edge of the 10 sheet moves upwardly over the face of the table 51.

The gages on the chute and table enable the sheet to be quickly and accurately squared to the platen and gaged as to its 15 position lengthwise of the platen. The sheet is also moved by hand backwardly or forwardly to position it for the first line of writing, in which position it may then be held by one hand of the operator, as indicated 20 in Fig. 3, wherein the finger 59 engages the right-hand margin of the sheet 60 and holds it against the roughened surface 57. Displacement of the adjusted sheet is thus prevented while the outer or original 25 sheet 61 is placed on the machine by the other hand of the operator and adjusted in a manner similar to that just described in connection with sheet 60. The outer sheet, which may be a leaf of a loose-leaf ledger, 30 and which may contain the entries for a number of the bills or invoices, will be adjusted with its leading edge a greater or less distance in advance of the underlying invoice or statement, so that the typewritten 35 entry on the ledger sheet will appear at the proper position below the preceding entries. The entries on the ledger sheet are usually made in vertical columns, having appropriate headings, which columns may 40 or may not be ruled; the same arrangement being carried out on the bill or invoice. It thus becomes important that the ledger sheet be in accurate register with the underlying sheet, so that the entries will appear 45 in correct position on the latter. The arrangement herein disclosed enables the quick and accurate adjustment and arrangement of the sheets in proper register. When the original sheet 61 has been positioned, as 50 above described, the feed-roll release key 17 is returned, so that the feed rolls grasp the sheets and coöperate in the usual manner with the platen to hold the sheets in their proper relative position, and advance 55 them over the platen when the latter is rotated.

The usual carbon sheet 62 is interposed between the sheets 60 and 61; the sheet 62 being conveniently adjusted as a unit with 60 the sheet 61. It will also be understood that the bill or invoice may, in some instances, overlie the ledger sheet, so as to receive the original impression. The invention has been described in detail in connection with 65 an invoice or bill and a ledger sheet, but

these provide merely one example of the various uses to which the invention is adapted.

The unit 60 may consist of one, two or more sheets, with the required number of 70 interleaved carbons, and often in practice consists of a folded sheet, making, in effect, two leaves caught together by their edges, and having an interleaved carbon; and, when desired, one folded sheet can be inserted 75 within the fold of another folded sheet, making altogether four leaves, with suitably placed carbons. The outer sheet 61 may also be made up in the same way, if desired; and in any case the carbon 62 may make the type- 80 written impressions upon the topmost sheet of the underlying unit 60. The webs marked 34, 35 may be of a width approximating the width of the ledger sheet 61, so as to receive all or nearly all of the record that is written 85 upon the ledger sheet, and after the roll or web is filled with writing it may be severed into leaves to form a record book for convenient reference, or otherwise used. In case 90 said webs 34, 35 are of a width approxi- 95 mately equal to the width of the ledger sheet 61, as aforesaid, (which may be done when the spools 37, 38 are made of suitable length for that purpose), all of the sheets may be fed around the platen in the usual manner, 100 and the winding spool 38 will wind up the webs. If said spool 38 should not wind the webs up as rapidly as they are delivered from the platen, the loose portions of the webs may be taken up by repeated operations 105 of the line-spacing handle 13, after the sheets 60, 61, 62 have been removed from the machine. Or if it is desired to take up the slack in the webs while all the sheets are still in the machine, the finger-piece 17 may be de- 110 pressed, to cast off the pressure rolls 16, and then said line-spacing handle 13 may be operated to revolve the spool 38 and take up the slack of webs 34, 35; the platen 5 being re- 115 volved idly by the line-spacing mechanism at this time, without advancing the ledger sheet, because of the released condition of the feed- 120 ing rolls 16. Where, however, it is not necessary to preserve upon the web all of the items that are entered upon the ledger sheet, as for instance, the "Previous Balance," the "Re- 125 ferences," and the "Present Balance," a narrow web may be employed, of a width to take in only the columns headed "Date," "Terms," "Charges" and "Credits," and in that case 130 the spools 37, 38 need not be lengthened, as they are shown sufficiently long to accommodate such a narrow web, and said web may pass around the platen without coming within the field of action of the feed rolls 16, 125 which, as seen in Fig. 1, are sufficiently separated to clear any web whose width is not greater than the length of said spools 37, 38; and in the case of use of such narrow web or record, the line-feeding of the web would 135

be effected by the winding action of spool 38, independently of the progress of the temporary work-sheets 60, 61, 62 through the machine, since the feed rolls 16 would control only said work-sheets 60, 61, 62, and would not control such narrow webs 34, 35, which could therefore advance at a rate slower than the advance of said work-sheets 60, 61, 62, so that there would occur no slack 10 in the webs 34, 35.

In practice, the feed roll 16 is first released, and the units 60, 61 are first assembled and then dropped together into the chute 25, 28, whereby they are guided around the 15 underside of the platen, and up onto the alining table 51. Enough of the side portion of the underlying unit 60 is visible to enable the operative to perceive when it is brought to position to receive the first line of writing; and, the sheets still being loose, he can readily adjust them so that the first line of writing on said underlying unit is brought 20 into register with the usual front scale 65 of the Underwood typewriting machine, to 25 which the present invention is shown applied. While the operative by means of his thumb 59 maintains said underlying unit 60 in this printing position, he uses his left hand to adjust the outer unit 61 either up or 30 down, to bring the first line thereon into position to be struck by the types 11; and to facilitate this adjustment, the face of the underlying unit 60 is provided with a vertical row of scores 63 to register exactly with 35 the rulings or scores 64 placed or extending into the right-hand margin of the outer sheet or unit 61. Then both units may be held by the left hand while the right hand restores the pressure roll 16. Thereupon the writing of 40 the various items may proceed, and the units then removed from the machine, although of course the web 34, or cumulative record sheet upon which the reference copy is made, remains in the machine, so that it may receive 45 or accumulate the copies of succeeding bills. In practice, the units 60 and 61 remain assembled when out of the machine, usually for the entire month; said units being from time to time replaced in the machine for receiving 50 additional entries.

When the writing is to be done near the top of the units, as for instance, when starting to write the first line upon a statement, there is not enough of the sheet or unit extending up alongside of the left-hand squaring-gage 55 to enable the sheet to be squared properly, with regard to the printing line on the platen, that is, the line along which the types 11 strike; but the sheets are nevertheless squared to said printing line by the coöperation of the gage 55 with the left-hand ledge or side 28 of the chute, said members 55 and 28 being in alinement, and forming together a complete side-edge squaring-gage, which is arranged partly at

the introductory side of the platen and partly at the delivery side of the platen; and it will be understood that the side-edge gage or gages of the chute 28 may be prolonged under the platen and up in front 70 thereof as indicated in section at 55, Fig. 3, so that the edge gage may, if desired, be continuous from the top of 28 to the top of 55; although, of course, so long as the effect of a continuous gage is secured, it would be 75 permissible to omit the portions of the gage at intervals, if desired.

At the end of the month the statement may be sent to the customer, and in case the ledger sheet is not filled up, the same may 80 be used for the succeeding month; and in that case, a fresh statement or unit may be dropped into the machine, together with the ledger sheet, and the statement-unit 60 may be first positioned in the manner already described, and then the sheet may be pulled up so that its top edge is considerably 85 above the top edge of the statement-unit 60, so as to bring the first blank line on the ledger-unit into overlying register with the 90 first line on the statement sheet, that is, the place thereon which is to receive the first line of writing. It will be understood that Fig. 3 is diagrammatic, and that the sheets when being collated are arranged in the machine in position to receive immediately the 95 first line of writing; that is to say, the first blank line below the typewriting appearing on 61 at Fig. 3 would be in register with the top of the scale 65, instead of being far 100 above said scale, as indicated diagrammatically.

It will be seen that the right-hand roughened portion 57 at Figs. 1 and 3 constitutes an extension of the board or table 51 used 105 in holding the sheet 60; the latter being widened for engagement with this roughened extension of the board, and the roughness enabling the sheet to be retained against edgewise displacement during the collation 110 of another sheet thereon. The table 51 is of extensive area to give room for collating sheets thereon, and is therefore distinguished from the relatively small tablets heretofore employed merely for locating the 115 leading edges of single sheets relatively to the printing line on the platen, as shown for example in the patent to Lundeberg, 1,113,227, of October 13, 1914. The width-wise capacity of the means for carrying the 120 record web or sheet 34 approximates that of the board 51, since 34 is a general record of every transaction in detail, and therefore distinguished from the narrow tally-strip shown in said Lundeberg patent as underlying one end of the leading-edge-adjusting tablet, and intended to keep a tally of the 125 totals.

This roughened portion of strip at 57 is 130 illustrated as arranged at one side of the

- web 34, since the sheet 60 has an extended side border for engaging this roughened strip, said border projecting to one side of said web 34.
5. A sheet may be gaged or collated against either gage 55 or 56, and in either case there is provided at the opposite side of the table a device 57 for use in holding a sheet against displacement while another sheet is collated thereon.
- One of the features of novelty resides in collating one sheet upon another in the desired relation as set forth, and collating these two upon a third, and providing for 15 reduced line-spacing of the third sheet only, to have it serve the purpose of a condensed record, to remain in the machine to receive successive records of successive sets of collated sheets.
- 20 Variations may be resorted to within the scope of the invention, and portions of the improvements may be used without others.
- Having thus described my invention, I claim:
- 25 1. A collating device for a front-strike typewriting machine, comprising, in combination, a revoluble platen, a chute at the rear of the platen for receiving work-sheets and extending under the platen to guide the 30 sheets forwardly around the platen, and a collating table extending upwardly and rearwardly from the delivery side of the platen, said table having an extensive area for collating sheets in various relationships 35 thereon, and having at one side a gage of sufficient extent to serve as a main gage for squaring a sheet by its side edge; said chute in position to direct the sheet to said gage, said table being provided along its opposite 40 side edge with a device to be used in holding an adjusted wide sheet against displacement while a narrow sheet is collated thereon; and said holding device comprising a lateral extension of the table and means upon said 45 lateral extension for engagement with the sheet.
2. In a collating device for a front-strike typewriting machine, the combination with a roller platen, of a collating board or table 50 extending upwardly and rearwardly from the front face of the platen and of extensive area to support and guide work-sheets to be collated, said table terminating at one side in an extensive main gage for the lateral 55 edge of a work-sheet, whereby alone the latter may be squared to the platen, said gage also enabling the collation of an outer sheet on said table in register with and overlying the first-mentioned sheet, said table being 60 provided with an extension along its side opposite from said gage, and said extension having a roughened surface to engage the first sheet and enable it to be securely held in adjusted position during the collation of 65 the second sheet.
3. In a typewriting machine, in which the types strike against the front face of a roller platen, the combination with said platen, of a work-supporting table extending upwardly and rearwardly from the front face of the 70 platen at a point above the writing line, said table provided with a lateral gage for the side edge of a work-sheet supported on the table, said gage also serving to gage an overlying sheet adjusted on said table while the 75 first sheet is held stationary in said adjusted position, said table provided with holding means to engage the first sheet, for holding it against edgewise displacement during the adjustment of the overlying sheet. 80
4. In a typewriting machine, in which the types strike against the front face of a roller platen, the combination with said platen, of a chute extending upwardly and rearwardly from the rear side of the platen and having 85 an extension curved around the platen and spaced therefrom to provide a passageway through which sheets placed on the chute may be guided around the platen, and a work-supporting table extending upwardly 90 and rearwardly from the front face of the platen, said chute and table each provided with side flanges extending upwardly from the sheet-supporting surfaces, the flanges on said table being respectively in alinement 95 with and forming substantial continuations of the corresponding flanges on the chute, and the table provided with means to engage the sheet to hold it against accidental advance or retraction. 100
5. In a typewriting machine, the combination with a roller platen, of a work-sheet supporting table extending upwardly and rearwardly from the platen, the lower edge of said table extending along the platen 105 above the printing line, the upper intermediate portion of said table being cut away so that the table comprises a comparatively narrow body portion extending along the platen, the ends of the table being extended 110 in a direction transverse to the platen to a substantial distance beyond said body portion and providing extended surfaces to support the side margins of a work-sheet, one of said extended surfaces being roughened 115 to permit the work-sheet to be securely held in adjusted position on the table, the table being formed with end flanges along said extended portions and forming gages for the lateral edges of the work-sheets. 120
6. In a typewriting machine, the combination with a roller platen, of means for positioning work-sheets thereon while the platen is at rest, said means comprising a chute at the introductory side of the platen, said chute extended around the under surface of the platen and spaced therefrom, a work-supporting table at the front side of the platen to receive the leading ends of the work-sheets, a gage on said table to which 125 130

- the sheets are adjustable, feed rolls to bear against the platen, means for casting said rolls off the platen to permit said positioning and adjustment of the sheets, and tally-
5 strip mechanism for supporting a tally-strip in position to extend around the platen between the platen and said work-sheets, so that the latter, when in said adjusted position, will overlie the tally-strip.
- 10 7. In a front-strike typewriting machine, the combination with a revoluble platen, of a collating board extending upwardly from the delivery side of the platen, and having at one side a gage to which to adjust the side
15 portions of the sheets to be collated, and a chute arranged at the introductory side of the platen and extending forwardly around the underside of the platen to guide the sheets to said collating board; the head of
20 said collating board being clear, to permit the ready adjustment thereon of sheets projecting beyond said head, and said gage being of sufficient extent to enable the sheets to be squared to the platen thereby, and said
25 chute comprising side guides arranged to deliver the sheets approximately to said gage.
8. The combination with a revoluble platen, of a side gage extending substantially continuously from the introductory
30 side of the platen to the delivery side thereof, and a table at the delivery side of the platen upon which a sheet may be squared by its side edge to said gage, said table terminating at one side in said gage.
- 35 9. In a typewriting machine, the combination with a revoluble platen, of means for supporting a work-piece thereon in position to lie against the platen along the printing line, a sheet-collating table at the delivery
40 side of the platen, means for receiving a second work-piece at the intake side of the platen and guiding it around the platen and past the printing line to bring its leading end onto said table while the platen is held
45 stationary with said first-mentioned work-piece positioned thereon, and means to gage said second work-piece on said table so that it will overlie the first-mentioned work-piece along the printing line.
- 50 10. In a typewriting machine, the combination with a revoluble platen, of means for supporting a work-piece thereon in position to lie against the platen along the printing line, a sheet-collating table at the delivery
55 side of the platen, means for receiving a second work-piece at the intake side of the platen and guiding it around the platen and past the printing line to bring its leading end onto said table while the platen is held
60 stationary with said first-mentioned work-piece positioned thereon, a gage on said work-table to which said second work-piece may be adjusted, and means to enable said second work-piece to be held in adjusted
65 position while a third work-piece is ad-
- vanced around the platen from the intake side thereof to bring its leading end onto the sheet-collating table, and adjusted over said second work-piece, all of the work-pieces, when thus adjusted, extending in superposed relation along the printing line.
11. In a typewriting machine, the combination with a revoluble platen, of means for supporting a continuous web in position to extend around the platen and lie thereagainst at the printing line, a sheet-collating table at the delivery side of the platen, a chute for receiving a work-piece at the introductory side of the platen and guiding it around the platen and past the printing line to bring its leading end onto said table while the platen is held stationary with said web thereon, said table so positioned that the work-sheet when adjusted thereto will overlie the said web along the printing line, sheet-feeding means to advance said sheet over the platen, and mechanism connected with said sheet-feeding means for concomitantly feeding said web.
12. In a front-strike typewriting machine, the combination with a roller platen, of a work-sheet collating board or table extending upwardly and rearwardly from the delivery side of the platen and of extensive area to permit the collation of work-sheets thereon, said collating board having means projecting from said board and extending along certain of its side borders and capable of use for adjusting all of the sheets relatively to the platen and holding a sheet against edgewise displacement while another sheet is collated thereon, and mechanism located behind said board to line-feed a record-web or work-piece which passes up in front of the platen and back of said board, to underlie the over-lying collated sheets and remain in position upon the platen when the sheets collated thereover are removed, whereby the record work-piece may receive the records of a succession of sets of collated sheets.
13. In a typewriting machine, the combination with a roller platen and feed-rolls therefor, of a chute at the introductory side of the platen, said chute extending around the under surface of the platen, a collating table at the delivery side of the platen in position to receive sheets introduced through said chute, said table having extensive area to permit collating of sheets thereon and terminating at one end in a lateral gage to which the side edge of the sheet is adjustable, said gage of sufficient extent to enable the sheet to be squared to the platen thereby, said feed-rolls sufficiently near said table to grip the sheets in the positions in which they are collated on said table, and means for casting off the feed-rolls to enable said sheets to be introduced into the machine while the platen is at rest, and to enable the adjust

ment of the sheets relatively to each other while within the bite of the feed-rolls.

14. The combination with a revoluble platen and a feed roll to run thereon below the printing line, of a tangential collating board extending upwardly and rearwardly from the vicinity of the printing line on the platen and terminating in a collating gage for the side edges of the sheets, said board, 10 gage and roll being disposed with reference to one another and to said platen to permit the sheets to be collated to said gage while extending between the platen and the roll, said collating board comprising means extending therefrom for engagement with the 15 side margin or border portion of a sheet laid thereon to enable the sheet to be positively held against displacement after being set to said gage and while the sheet collated upon 20 the first sheet is being also set to said gage, and said gage having sufficient extent to enable the sheets to be thereby readily squared to the platen; and means to release said feed roll to permit the collation of sheets between 25 the roll and platen.

15. The combination with a revoluble platen and a releasable feed roll to run thereon, of a tangential collating board extending upwardly and rearwardly from the vicinity 30 of the printing line on the platen, and having means extending therefrom and rigid therewith to be engaged by the work-sheet and capable of use for gaging the side edge of the sheet and holding the sheet positively 35 against accidental upward and downward displacement along the board while a second sheet is being collated thereon; said board, said gaging and holding means and said roll being disposed with relation to one another 40 and to the platen to permit the sheets to be so collated while extending between the platen and the roll, and said gaging means having sufficient extent to enable the sheets to be thereby readily squared to the platen.

16. In a front-strike typewriting machine, the combination with a revoluble platen, of an introductory chute arranged at the rear of the platen and extending upwardly from the platen and comprising a floor portion 50 and sides to confine the sheets and guide them forwardly to the printing line, a feed roll on the platen, a sheet-collating board in position to receive sheets introduced through said chute and extending upwardly and rearwardly from the vicinity of the printing line of the platen and clear at its upper edge and terminating at one side in a collating gage for the side edges of the sheets, said gage coincident with one side 55 of the chute, said board, gage and roll being disposed with reference to one another and to said platen to permit the sheets to be collated to said gage while extending between the platen and the roll, said board provided 60 with means for engagement by the side bor- 65 der portion of the sheet to enable the sheet to be held against displacement after being set to said gage, and while a superposed sheet is being collated to said gage; and means to release said roll to permit the collation of the sheets 70 on said board while the sheets extend between the roll and platen.

17. In a front-strike typewriting machine, the combination with a revoluble platen, of an introductory chute arranged at the rear 75 of the platen and extending upwardly from the platen and comprising a floor portion and sides to confine the sheets and guide them forwardly to the printing line, a releasable feed roll on the platen, and a sheet-collating board extending upwardly and rearwardly from the vicinity of the printing line of the platen and terminating at one end 80 in a collating gage for the side edges of the sheets, said gage coincident with one side of 85 the chute, said board, gage and roll being disposed with reference to one another and to said platen to permit the sheets to be collated to said gage while extending between the platen and the roll, said board having a 90 roughened surface extending along the side thereof opposite from said gage, against which the operative may depress the corresponding side margin of the first work-sheet, 95 to secure the same while collating a superposed sheet to said gage.

18. In a front-strike typewriting machine, the combination with a revoluble platen, of an introductory chute arranged at the rear of the platen and extending upwardly from 100 the platen, and also extending forwardly under the platen to guide the sheets forwardly to the printing line, a releasable feed roll on the platen, and a sheet-collating board extending upwardly and rearwardly 105 from the vicinity of the printing line of the platen and having at each side a collating gage and means capable of use for holding the side borders of the sheets, said board, gage and holding means and said roll being 110 disposed with reference to one another and to said platen to permit the sheets to be collated to said gage and holding means while extending between the platen and the roll.

19. The combination with a revoluble 115 platen and a releasable feed roll to run thereon, of a collating board extending away from the platen at the vicinity of the printing line and terminating at one side in a collating gage for the side edges of 120 the sheets, said collating board provided along its side opposite from said gage with a roughened surface to be engaged by the under side of the first collated sheet, to hold the same against accidental advance or 125 retraction, while a superposed sheet is being collated to said gage, said board, gage and roll being disposed with reference to one another and to said platen to permit the sheets to be collated to said gage while ex- 130

tending between the platen and the roll, said gage having sufficient extent to enable the sheets thereby to be readily squared to the platen.

5 20. The combination with a revoluble platen, a scale therefor, and a releasable feed roll to run thereon, of a collating board extending away from the platen at the vicinity of the printing line and terminating 10 at one side in a collating gage for the side edges of the sheets, said collating board provided along its opposite sides with a roughened surface to be engaged by the under side of the first collating sheet to hold the 15 same against accidental upward or downward displacement, while a superposed sheet is being collated to said gage, said board, gage, scale and roll being disposed with reference to one another and to said platen 20 to permit the sheets to be collated to said gage by the aid of said scale, and while extending between the platen and the roll, said gage having sufficient extent to enable the sheets thereby to be readily squared to 25 the platen.

21. In a typewriting machine, the combination with a revoluble platen, of a tangential collating table extending upwardly and rearwardly from about the printing 30 line on the platen, and terminating in a side gage, said gage being sufficiently prolonged above the body portion of the collating table to enable a work-sheet to be squared to the platen thereby, said table provided with 35 means to be engaged by a work-sheet and capable of use in holding the sheet against accidental advance or retraction during the collation of a superposed sheet to the gage.

22. In a typewriting machine, the combination with a revoluble platen, of a tangential collating table extending upwardly and rearwardly from about the printing line on the platen, and terminating in opposite side gages, said gages being substantially 40 prolonged above the body portion of the collating table to enable a work-sheet to be squared to the platen by either gage, and said collating table having extensions rising from its side portion adjacent to said collating gages, said extensions provided with 45 means to be engaged by a work-sheet and capable of use in holding the sheet against accidental advance or retraction during the collation of a superposed sheet to the gage, 50 the distance between said extensions being sufficient to afford to the operator access to the rear of the platen to introduce sheets into the machine.

23. In a typewriting machine, the combination with a revoluble platen, of a chute extending downwardly to the rear of the platen and forwardly under the same, and having a floor and sides for guiding sheets to the printing line on the front of the 55 platen, and a tangential collating table ex-

tending upwardly and rearwardly from about the printing line on the platen, and terminating in a side gage coincident with a side of the chute, said gage being substantially prolonged above the body portion of the 70 collating table to enable a work-sheet to be squared to the platen thereby, said table provided, upon the side opposite from said gage, with means to be engaged by a work-sheet and capable of use in holding 75 the sheet against accidental advance or retraction during the collation of a superposed sheet to the gage.

24. In a typewriting machine, the combination with a revoluble platen, of a chute 80 extending downwardly to the rear of the platen and forwardly under the same, and having a floor and sides for guiding sheets to the printing line on the front of the platen, and a tangential collating table extending upwardly and rearwardly from about the printing line on the platen, and terminating in opposite side gages coincident with the sides of the chute, said gages being substantially prolonged above the 85 body portion of the collating table to enable a work-sheet to be squared to the platen by either gage, and said collating table having extensions rising from its side portion adjacent to said collating gages, said extensions provided with means to be engaged by a work-sheet and capable of use in holding 90 the sheet against accidental advance or retraction during the collation of a superposed sheet, the distance between said extensions 95 being sufficient to afford to the operator access to the chute to introduce sheets thereinto.

25. In a typewriting machine, the combination with a revoluble platen, of a record-web or sheet supporting and feeding mechanism to coöperate with said platen, a releasable feed-roll device to run upon the platen, a collating table extending from the delivery side of the platen, and means upon 100 said collating table to extend along side edges of the sheets and capable of use in laterally gaging and securing against displacement a sheet overlying the record-web, while another sheet is being collated upon 110 said overlying sheet.

26. In a typewriting machine, the combination with a revoluble platen, of a record-web or sheet supporting and feed mechanism to coöperate with said platen, 115 releasable feed rolls to run upon the platen one at each side of the record-web but clear of said web, and means for collating sheets upon said web, including a collating table extending from the delivery side of the 120 platen and laterally extending substantially beyond the sides of the record-web, said collating table terminating at one end, at a substantial distance laterally from the side edge of the record-web, in a lateral gage of 130

sufficient extent to enable a sheet to be squared thereby to the platen at the collating operation, said collating means also including means upon said table for use in holding one sheet against displacement while collating another sheet thereon.

27. In a typewriting machine, the combination of revoluble platen, mechanism for supporting and feeding a record-web or sheet around the platen so that the aggregate advance of the web may be less than that of the platen, releasable feed rolls to run upon portions of the platen not inclosed by the web, and means for collating sheets upon said web, including a collating table extending from the delivery side of the platen and terminating at its end in a lateral gage to which a work-sheet superposed upon the web may be laterally collated while extending between said feed rolls and the platen, said gage being of sufficient length to enable the sheet to be squared to the platen, said collating means also including means upon said table for use in holding one sheet against displacement while collating another sheet thereon.

28. In a front-strike typewriting machine, the combination with a revoluble platen, of mechanism for supporting and feeding a record-web or sheet around the platen, a releasable feed roll to run upon the platen, and means for gaging and securing sheets overlying said web, including a collating table extending from the delivery side of the platen and terminating at its end in a lateral gage to which a work-sheet superposed upon the web may be collated by its side edge while extending between said feed roll and platen, said gage being of sufficient length to enable the sheet to be squared to the platen, and also including means at the side of the collating table opposite from the gage, to engage the work-sheet, for use in holding the sheet against accidental displacement during the collating of a superposed sheet.

29. In a front-strike typewriting machine, the combination of a revoluble platen, means in rear thereof for supporting and advancing a record sheet or web around the platen, a releasable feed roll to run upon the platen below the printing line, and a collating table extending upwardly from the delivery side of the platen and terminating at one end in a lateral gage to which a work-sheet superposed upon the record web may be collated by means of its side edge while extending between said feed roll and the platen, the end portions of the collating table being extended upwardly and thereby affording supports for the side margins of the collated sheets, such extended portions being sufficiently separated to afford access to the record web mechanism in rear of the platen, and said lateral

gage extending along one of said upwardly extended portions sufficiently to enable the sheets to be readily squared to the platen thereby.

30. In a front-strike typewriting machine, the combination of a revoluble platen, means in rear thereof for supporting and advancing a record sheet or web around the platen, a releasable feed roll to run upon the platen below the printing line, and a collating table extending upwardly from the delivery side of the platen and terminating at one end in a lateral gage to which a work-sheet superposed upon the record web may be collated by means of its side edge while extending between said feed roll and the platen, the end portions of the collating table being extended upwardly and thereby affording supports for the side margins of the collated sheets, such extended portions being sufficiently separated to afford access to the record web mechanism in rear of the platen, and said lateral gage extending along one of said upwardly extended portions sufficiently to enable the sheets to be readily squared to the platen thereby, and the other extended portion being provided with a holding device for enabling the operator to secure the sheet against accidental advance or retraction while collating another sheet thereon.

31. In a front-strike typewriting machine, the combination with a revoluble platen, of means for assembling, one after another, and line-feeding thereon, in superposed relation, a bookkeeping sheet, an item sheet or bill, with the item sheet and bookkeeping sheet in a variety of relative positions, and a general record sheet of a width approximating that of the item sheet, comprising (1) means for carrying a general record sheet around the platen, (2) means for line-feeding simultaneously the platen and the general record sheet, and (3) a collating table to overlie the record sheet and extending upwardly from about the printing line on the platen; the widthwise capacity of the record-sheet-carrying means approximating that of said table; and said collating table having thereon means to engage the side margins of the bookkeeping and item sheets to gage both sheets and square them to the platen and to enable one sheet to be held against edgewise displacement while the other is collated thereon.

32. In a front-strike typewriting machine, the combination with a revoluble platen, of means for assembling, one after another, and line-feeding thereon, in superposed relation, a bookkeeping sheet, an item sheet or bill, with the item sheet and bookkeeping sheet in a variety of relative positions, and a general record sheet of a width approximating that of the item sheet, comprising (1) means for carrying a general

- record sheet around the platen, (2) means for line-feeding simultaneously the platen and the general record sheet, and (3) a collating table to overlie the record sheet and 5 extending upwardly from about the printing line on the platen; the widthwise capacity of the record-sheet-carrying means approximating that of said table; said collating table having thereon means to engage the side margins of the bookkeeping and item sheets to gage both sheets and square them to the platen and to enable one sheet to be held against edgewise displacement while the other is collated thereon, said collating table having upwardly-extending sheet-supporting extensions at its ends, said extensions being sufficiently separated to afford access between them to the devices which hold the general record-web, and said sheet-gaging means extending along one of 10 said extensions.
35. In a front-strike typewriting machine, the combination with a revoluble platen, of means for assembling, one after another, and line-feeding thereon, in superposed relation, a bookkeeping sheet, an item sheet or bill, with the item sheet and bookkeeping sheet in a variety of relative positions, and a general record sheet of a width approximating that of the item sheet, comprising (1) means for carrying a general record sheet around the platen, (2) means 15 for line-feeding simultaneously the platen and the general record sheet, and (3) a collating table to overlie the record sheet and extending upwardly from about the printing line on the platen; the widthwise capacity of the record-sheet-carrying means approximating that of said table; said collating table having thereon means to engage the side margins of the bookkeeping and item sheets to gage both sheets and square 20 them to the platen and to enable one sheet to be held against edgewise displacement while the other is collated thereon, said line-feeding means including means for automatically advancing the bookkeeping sheet 25 and the item sheet to a greater extent than the general record-web, and means being provided to bear upon the platen outside of the field of the record sheet, for feeding the bookkeeping and item sheets at the speed of 30 the platen.
34. In a front-strike typewriting machine, the combination with a revoluble platen, of means for assembling, one after another, and line-feeding thereon, in superposed relation, a bookkeeping sheet, an item sheet or bill, with the item sheet and bookkeeping sheet in a variety of relative positions, and a general record sheet of a width approximating that of the item sheet, comprising (1) means for carrying a general record sheet around the platen, (2) means 35 for line-feeding simultaneously the platen and the general record sheet, and (3) a collating table to overlie the record sheet and 40 extending upwardly and about the print-
- ing line on the platen; the widthwise capacity of the record-sheet-carrying means approximating that of said table; said collating table having thereon means to engage the side margins of the bookkeeping and item sheets to gage both sheets and square them to the platen and to enable one sheet to be held against edgewise displacement while the other is collated thereon, said collating table having upwardly-extending sheet-supporting extensions at its ends, said extensions being sufficiently separated to afford access between them to the devices which hold the general record-web, and said sheet-gaging means extending along one of 45 said extensions.
36. In a front-strike typewriting machine, the combination with a revoluble platen and a releasable feed-roll to run thereon below the printing line, of means for assembling, one after another, and line-feeding thereon, in superposed relation, a bookkeeping sheet, an item sheet or bill, with the item sheet and bookkeeping sheet in a variety of relative positions, and a general record sheet of a width approximating that of the item sheet, comprising (1) means for carrying a general record sheet around the platen, (2) means 50 for line-feeding simultaneously the platen and the general record sheet, and (3) a collating table to overlie the record sheet and extending upwardly from about the printing line on the platen; the widthwise capacity of the record-sheet-carrying means approximating that of said table; said collating table having thereon means to engage the side margins of the bookkeeping and item sheets to gage both sheets and square them to the platen and to enable one sheet to be held against edgewise displacement while the other is collated thereon, and said gaging means being of sufficient extent and so arranged as to enable a sheet 55 to be squared thereby to the platen while the sheet extends between said platen and said feed-roll.
36. In a collating device for typewriting machines in which the types strike against the front face of the roller platen, the combination with a platen, of a chute extending upwardly and rearwardly from the rear side of the platen and having an extension curved around the platen, and a collating table extending upwardly and rearwardly from the delivery side of the platen, said chute and 60 table each provided with side flanges extending upwardly from sheet-supporting surfaces, the flanges on said table being respectively in alinement and forming substantially continuations of the corresponding flanges on the chute, and the table provided with means to facilitate the holding of one sheet against edgewise displacement while an overlying sheet is adjusted relatively thereto.

37. The combination with a revolute platen, of a collating board directed upwardly and rearwardly from the delivery side thereof, and having means extending therefrom with which the operative may engage an extended side border of one sheet, to retain said sheet in position upon said board while a superposed sheet is being located relatively to the retained sheet.
38. The combination with a revolute platen, of a collating board directed upwardly and rearwardly from the delivery side thereof, and having means extending therefrom with which the operative may engage an extended side border of one sheet, to retain said sheet in position upon said board while a superposed sheet is being located relatively to the retained sheet, and a feed-roll to run upon the platen, said roll releasable to permit the collation of the sheets, and mounted in position to clamp the sheets against the platen before they are released from control at the collating board.
39. In a front-strike typewriting machine, the combination with a roller platen, of a work-sheet collating board extending upwardly and rearwardly from the delivery side of the platen, and of extensive area to permit the collation of work-sheets thereon, and means projecting from said board and extending along certain of its side borders and capable of use for adjusting all of the sheets relatively to the platen and holding a sheet against edgewise displacement while another sheet is collated thereon.
40. A collating device for a front-strike typewriting machine comprising, in combination, a revolute platen, and a collating table extending upwardly and rearwardly from the delivery side of the platen, said table having an extensive area for collating sheets in various relationships thereon, and having at one side a gage of sufficient extent to serve as a main gage for squaring a sheet by its side edge; said table being provided along its opposite side edge with a device to engage a wide sheet for use in retaining the same while a narrow sheet is collated thereon; said retaining device comprising a lateral extension of the table and means upon said lateral extension for engagement with the sheet.
41. The combination with a revolute platen, of means for collating at least three work-sheets preparatory to the typing operation, said collating means including a collating board extending from the delivery side of the platen and of extensive area to permit the collation of sheets thereon, and also including means for use in holding the bottom or inner work-sheet while the intermediate work-sheet is collated thereon, and both bottom and intermediate work-sheets while the outer or top work-sheet is collated thereon; said work-sheet holding means including means in rear of the collating board for holding the bottom work-sheet as it extends up between the board and platen.
42. The combination with a revolute platen, of means for collating at least three work-sheets preparatory to the typing operation, said collating means including a collating board extending from the delivery side of the platen and of extensive area to permit the collation of sheets thereon, and also including means for use in holding the bottom or inner work-sheet while the intermediate work-sheet is collated thereon, and both bottom and intermediate work-sheets while the outer or top work-sheet is collated thereon; said work-sheet holding means including means in rear of the collating board for holding the bottom work-sheet as it extends up between the board and platen.
43. The combination with a revolute platen, of means for collating at least three work-sheets preparatory to the typing operation, said collating means including a collating board extending from the delivery side of the platen and of extensive area to permit the collation of sheets thereon, and also including means for use in holding the bottom or inner work-sheet while the intermediate work-sheet is collated thereon, and both bottom and intermediate work-sheets while the outer or top work-sheet is collated thereon; said work-sheet holding means including means in rear of the collating board for holding the bottom work-sheet as it extends up between the board and platen, and also including means extending along certain of the side borders of the collating board for engaging the second work-sheet.
44. The combination with a revolute platen, of means for collating at least three work-sheets preparatory to the typing operation, said collating means including a collating board extending from the delivery side of the platen and of extensive area to permit the collation of sheets thereon, and also including means for use in holding the bottom or inner work-sheet while the intermediate work-sheet is collated thereon, and both bottom and intermediate work-sheets while the outer or top work-sheet is collated thereon; said work-sheet holding means including means in rear of the collating board for holding the bottom work-sheet as it extends up between the board and platen, and also including means extending along certain of the side borders of the collating board, and arranged at one side of the bottom work-sheet for engaging the second or intermediate sheet.
45. The combination with a revolute platen, of means for collating at least three work-sheets preparatory to the typing operation, said collating means including a collating board extending from the delivery side of the platen and of extensive area to permit the collation of sheets thereon, and also including means for use in holding the bottom or inner work-sheet while the intermediate work-sheet is collated thereon, and both bottom and intermediate work-sheets while the outer or top work-sheet is collated thereon; said work-sheet holding means including means in rear of the collating board for holding the bottom work-sheet as it extends up between the board and platen.

mediate work-sheet is collated thereon, and both bottom and intermediate work-sheets while the outer or top work-sheet is collated thereon; said work-sheet holding means including means in rear of the collating board for holding the bottom work-sheet as it extends up between the board and platen, and also including means extending along certain of the side borders of the collating board, 10 and arranged at one side of the bottom work-sheet, for engaging the second or intermediate sheet, the widthwise capacity of said means for holding the bottom sheet being nearly co-extensive with that of said collating board.

46. The combination with a revoluble platen, of means for collating at least three work-sheets preparatory to the typing operation, said collating means including a collating board extending from the delivery side of the platen and of extensive area to permit the collation of sheets thereon, and also including means for use in holding the bottom or inner work-sheet while the intermediate work-sheet is collated thereon, and both bottom and intermediate work-sheets while the outer or top work-sheet is collated thereon, and means for line-spacing the bottom sheet at a slower speed than the upper sheets.

47. The combination with a revoluble platen, of means for permanently retaining a work-sheet in position upon said platen, and means for collating a plurality of work-sheets upon said permanently-retained work-sheet; whereby a record may be kept upon the permanently-retained work-sheet of items typed upon a plurality of sets of collated work-sheets; said collating means including a collating board extending from the delivery side of the platen, and also including means for use in retaining one adjusted sheet while another is collated thereon.

48. The combination with a revoluble platen, of means for permanently retaining a bottom work-sheet in position upon said platen, and means for collating a plurality of work-sheets upon said permanently-retained work-sheet; whereby a record may be kept upon the permanently-retained work-sheet of items typed upon a plurality of sets of collated work-sheets; said collating means including a collating board extending from the delivery side of the platen, and also including means for use in retaining one adjusted sheet while another is collated thereon, and said means for permanently retaining the bottom work-sheet being arranged in rear of the collating board, 60 said bottom sheet lying between the collating board and the platen.

49. In a front-strike typewriting machine, the combination with a revoluble platen, of means for assembling in superposed relation 65 a bookkeeping sheet, an item sheet or bill,

with the item sheet and bookkeeping sheet in different relative positions, and a general record sheet upon which all entries on the other sheets may appear in the order in which they are written, comprising (1) means for carrying a general record sheet in web form around the platen, and (2) a collating table having provision for the adjustment of sheets in various superposed relations thereon and squaring such sheets to the platen and holding a squared sheet against edgewise displacement while another is collated thereon, said table extending upwardly from about the printing line of the platen, on which table the bookkeeping and item sheets may be collated, and the web-carrying means and the collating table being of such relative extent and so arranged that both the amounts and the words typewritten thereagainst upon the item and bookkeeping sheets may be duplicated upon the general record web.

50. In a front-strike typewriting machine, the combination with a revoluble platen, of means for assembling and line-feeding thereon in superposed relation a bookkeeping sheet, an item, bill or sheet, with the item sheet and bookkeeping sheet in different relative positions, and a general record sheet upon which all entries on the other sheets may appear in the order in which they are written comprising (1) means for carrying a general record sheet in web form around the platen, and (2) a collating table having provision for the adjustment of sheets in various superposed relations thereon and squaring such sheets to the platen and holding a squared sheet against edgewise displacement while another is collated thereon, said table extending upwardly from about the printing line on the platen on which the bookkeeping and item sheets may be collated, and the web-carrying means and the collating table being of such relative extent and so arranged that both the amounts and the words typewritten thereagainst upon the item and bookkeeping sheets may be duplicated upon the general record web, said line-feeding means including means for automatically advancing the bookkeeping sheet and the item sheet to a greater extent than the general record web.

51. In a typewriting machine, the combination with a platen roller, of a work-sheet collating table extending upwardly and rearwardly from the front face of the platen, and record web-supporting mechanism located behind said table and comprising a winding spindle and a supply roll from which a web may extend around the platen past the printing line and upwardly between the platen and said collating table and thence to the winding spindle, whereby the web underlies a work-sheet positioned on the platen with its leading end supported on

- said collating table, said table provided with means enabling sheets to be collated without interference with said web, said collating means including provision for the adjustment of sheets in various superposed relations thereon and squaring such sheets to the platen and holding a squared sheet against edgewise displacement while another is collated thereon.
- 10 52. In a typewriting machine, the combination with a roller platen and feed-rolls therefor, of means for collating work-sheets, said means comprising a collating table at the front side of the platen, said table having provision for the adjustment of sheets in various superposed relations thereon and squaring such sheets to the platen and holding a squared sheet against edgewise displacement while another is collated thereon,
- 15 20 means for casting off the feed-rolls to enable sheets to be introduced into the machine while the platen is stationary, and to enable said sheets to be collated on said collating table while said sheets are within the bite 25 of the feed-rolls, and a record web-support-
ing mechanism located behind said collating table, from which the web may extend around the platen and past the printing line and upwardly between the platen and said table, whereby the web underlies a work- 30 sheet positioned on the platen with its leading end supported by said collating table.
53. In a typewriting machine, the combination with a roller platen and feed-rolls therefor; of means for collating work- 35 sheets, said means comprising a collating table at the front side of the platen having means thereon to facilitate the holding of a work-sheet against endwise displacement during adjustment of an overlying work- 40 sheet relatively thereto, and including means for casting off the feed-rolls to enable said sheets to be introduced into the machine while the platen is stationary and to enable edgewise adjustment thereof while said 45 sheets are within the bite of the feed-rolls.
